METHOD AND APPARATUS FOR FELT CONDITIONING

Thomas S. Jordan, Springhill, La.

Application August 20, 1941, Serial No. 407,519½

7 Claims. (Cl. 92—50)

It is an object of my invention to provide a felt conditioner which will produce effective results on high speed felts.

It is a further object of my invention to provide a felt conditioner which can be operated with its surface either horizontal or vertical or at any desired angle intermediate horizontal and vertical.

Further objects of my invention are to provide a felt cleaner which is cheap and easy to manufacture; has a minimum number of parts; is subject to a minimum of wear; and can be kept in operation indefinitely by replacement of a single cheap and simple part.

The accomplishment of these and other objects will be made clear from the following detailed description taken in connection with the annexed drawings, in which—

Figure 1 is a view in elevation showing my improved felt cleaner in operative position in a typical felt installation;

Fig. 2 is an enlarged view in elevation of my felt cleaner;

Fig. 3 is a plan view;

Fig. 4 is a view similar to Fig. 3 with the cover plate of the vacuum chamber removed;

Fig. 5 is a view similar to Fig. 2, with the cover plate of the water chamber removed;

Fig. 6 is an end elevation of my cleaner with the cover removed; and

Fig. 7 is a section taken on the line 7—7 of Fig. 3.

In various types of paper-making machines the newly formed wet web is carried from the web-forming device, which may be of any type such, for example, as the familiar cylinder or Fourdrinier machines, and is passed through press-rolls. At this stage the web contains about 85% moisture and is extremely fragile, so that woolen felts are used to carry the wet web through the press rolls. Most of the water extracted by the press-rolls is driven through these felts, and carries with it fiber, filler, and other solids and colloids from the paper stock, which materials lodge in the face of the felt. If no felt cleaner were provided, the nap of the felt would shortly become matted and almost glazed, the felt would not properly transmit the water extracted by the press-rolls and would mark the surface of the wet web.

The most important characteristic of the felt is its ability to transmit water. This water is actually driven through the entire thickness of the felt, and since the water carries both in suspension and solution a substantial quantity of

paper making material, such material penetrates the entire thickness of the felt. Naturally, the felt acts as a filter, and therefore the greatest concentration of paper making material occurs at the surface, but, in time, there is a substantial distribution of such material throughout the thickness of the felt. This material, under the tremendous force of the press rolls tends to fill the interstices of the felt and thus to reduce its penetrability. The material in solution tends to raise the viscosity of the liquid above that of pure water, and in other ways, too, sets up resistance to its flow. This tends to prevent the cleaning fluid supplied by the conditioner from penetrating the interstices of the felt and thus works against the effective cleaning away of all undesirable material. When the penetrability is too far reduced, the felt renders the press rolls ineffective to remove the proper amount of water from the paper web. At this point, the machine must be stopped and the felt must be removed and washed. This is an adverse effect wholly in addition to the effect of extraneous materials on the surface characteristics.

It is customary to provide some device which will tend to recondition the active surface of the felts by removing the solids extracted from the paper and by restoring the proper condition of the nap. The devices heretofore used have been reasonably satisfactory on relatively slow moving felts. Modern practice has, however, tended constantly to increase the lineal speed of the felts and these speeds have now become so great that conventional felt cleaners are no longer sufficiently effective.

It is clear that the period during which the felt is acted upon by the cleaner will decrease as the felt speed is raised. To maintain a proper cleansing and conditioning action, therefore, requires that the activity of the cleaner per unit of its surface must be increased so that equal or better results may be had in a lesser period of time. Practical considerations of space and cost limit the use of multiple cleaners. It is also a fact that cleaning heads which operate on the principle of supplying water to the felt and drawing it out again by vacuum face practical limits in the intensity of vacuum and in the quantity of water which may be supplied. The result is to cause more frequent shut-downs of the paper machine in order to permit removal and washing of the felt. These shut-down periods very seriously affect the economy of operations, and greatly lower the annual or monthly output of any given machine.

In my cleaner I take advantage of the principle that rapid alternation of the direction of flow of a cleaning fluid will loosen and remove more material per unit of time than will the same quantity of cleaning fluid moving in a single direction. The application of this principle to the physical design of my cleaner will be made clear hereinafter.

In Fig. 1 I show a pair of press-rolls 10 and a felt 12 passing between the rolls. On the return pass of the felt 12 it comes in contact with my felt cleaner indicated generally at 14. The felt cleaner 14 is conventionally secured to a bracket 16 which is slidably mounted on an angle iron 18. The bracket 16 and the cleaner 14 are moved transversely of the felt by a screw 20. This mounting and traversing of the cleaner is conventional and the patent to Vickery No. 1,553,274 shows the details of a typical installation of this sort. The conditioner as shown in Fig. 3 may optionally have either end as the leading end. It is, however, preferred that the larger opening 52, at the right hand end of Fig. 3, be made the trailing end. The speed of movement of the cleaner transversely of the felt is so regulated that the entire length of the felt passes over the surface of the cleaner during the time in which the cleaner moves transversely a distance equal to its own effective width. Conventional reversing mechanism operating on the screw 20 serves to carry the cleaner alternately back and forth across the felt.

As is perhaps best shown in Fig. 7, my cleaner consists of a casting 22 divided into a vacuum chamber 24 and a water chamber 26. A cover 28 secured by screws 30 closes the water chamber, and a cover 32 secured by cap screws 34 covers the vacuum chamber 24.

The cover 32 for the vacuum chamber 34 is preferably, though not necessarily, made of micarta and its outer surface is suitably smoothed for contact with the felt. "Micarta" is a product formed by laminating a number of fibrous sheets under pressure and bonding the same together with a suitable adhering medium.

At one end of the vacuum chamber 24 I provide a main vacuum connection 36 and at the other end an auxiliary vacuum connection 38. At the end of the water chamber 26 adjacent the main vacuum connection 36 I provide a water connection 40. Both vacuum and water connections are made through flexible conduits which permit the traversing movement of the cleaner.

In the casting 22 I provide a series of members 42, each of which extends transversely of the vacuum chamber 24, and each of which has an opening 44 extending axially thereof and communicating with the water chamber 26. On each member 42 is a boss 46 extending upwardly therefrom and having a slot 48 therein, which slot communicates with the opening 44.

The "Micarta" cover 32 has in it a series of slots 50, each of which registers with a slot 48 in one of the bosses 46. Water may therefore be delivered from the water chamber 26 through the openings 44 in the members 42 and through the slots 48 and 50 to the surface of the cover 32.

The cover 32 has formed in it a series of openings which communicate with the vacuum chamber 24. Certain of these openings, indicated at 52, are elongated and have their axes transverse the length of the cover 32. Certain other openings indicated at 54 are elongated and have their axes inclined relative to the length of the cover

32, and in addition I may optionally provide circular openings 56 at various points in the cover 32.

As the felt moves over the upper surface of the cover 32, it will receive a series of applications of water (or other cleaning fluid) through the slots 50, and this water will be extracted intermediate the slots 50 by the vacuum openings 52 and/or 54. In particular the inclined slots 54 produce a kneading action on the surface of the felt, thus loosening any solids adhering to the surface and facilitating the removal of such solids. This same kneading action tends to restore the nap of the felt to its proper condition. The relatively narrow dimensions of the slots in the direction of travel of the felt limit the deflection of the felt normal to the plane of the plate. The edges of the slots act as scrapers, and remove from the surface of the felt such materials as the vacuum draws to the surface from the interstices of the felt. The action is progressive throughout the several applications of vacuum and cleaning fluid. Each jet works into the fabric and loosens some of the foreign material. Instantly thereafter the vacuum pulls out all, or most of the injected fluid which carries with it some of the foreign matter, bringing such matter to the surface of the felt. The slot edges then scrape part of the material off the felt. By the time the last stage is reached, the water of the jets flows freely through the felt, and may be withdrawn with far less application of vacuum (in area) than is applied in conventional felt conditioners to extract the water added by only a single jet. The inclination of the slots 54 directly and substantially contributes to the scraping effect. It is clear that, with a rapidly moving felt (1,000 or more feet per minute), my cleaner, by providing a quick succession of applications and removals of cleaning fluid and by providing quick successive deflections of the felt in different directions, operates far more effectively to recondition a felt than any other cleaner shown in the prior art. The provision of the vacuum connections at both ends of the vacuum chamber is important since this permits uninterrupted application of the vacuum irrespective of the angular position of the cleaner and irrespective of the quantity of water being drawn into the vacuum chamber. It will be understood that there is a great deal more water available for withdrawal than is supplied through the water chamber, and a single vacuum connection, particularly when the cleaner is operated out of the horizontal, might be clogged by the water drawn into the vacuum chamber.

I do not intend to be limited to any particular number of openings nor to the use of any particular materials, nor to the formation of member 22 as a casting. The only limitation upon the scope of this invention will be as set forth in the subjoined claims which are to be broadly construed.

What is claimed is

1. A felt conditioner shoe including a plate adapted to contact a moving felt and of less width than the felt, there being in the surface of said plate in contact with said felt a plurality of means for supplying cleaning fluid to said felt and a plurality of means for applying vacuum to said felt; a single source of vacuum common to all of said vacuum applying means; said fluid supplying means and said vacuum applying means being alternated in a direction parallel to the travel of said felt, there being a suffi-

cient number of each of said means to provide a plurality of cycles of fluid supplying and vacuum extraction of the fluid supplied and to keep said source of vacuum flushed clean at all times.

2. A felt conditioner shoe including a plate adapted to contact a moving felt and of less width than the felt, there being in the surface of said plate in contact with said felt a plurality of means for supplying cleaning fluid to said felt and a plurality of means for applying vacuum to said felt; a single source of vacuum common to said means for applying vacuum to said felt; said fluid supplying means and said vacuum applying means being alternated in a direction parallel to the travel of the felt; there being a sufficient number of each of such means to provide a plurality of alternations of fluid supplying and vacuum extraction of the fluid supplied and to keep said source of vacuum flushed clean at all times; certain of said vacuum applying means being effective over elongated areas inclined to the path of travel of said felts.

3. A felt conditioner shoe comprising: an elongated vacuum chamber; an elongated water chamber parallel thereto; a series of spaced conduits running transversely of said vacuum chamber and communicating with said water chamber, all of said conduits being clear of the bottom of said vacuum chamber and having openings in their upper sides; a cover for said vacuum chamber, said cover having openings communicating with said vacuum chamber and other openings in registry with the openings in said conduits and said cover being mounted to form a seal between the openings in said conduits and said vacuum chamber; and pipe connections for each of said chambers.

4. A felt conditioner comprising a member elongated in the direction of travel of the felt, and of less width than the felt it is designed to treat, said member having means for injecting cleaning fluid into the felt, and means for extracting fluid therefrom, a vacuum chamber in communication with the last named means, and two vacuum applying connections for said chamber, said connections being spaced in the direction of travel of said felt, said chamber being shaped so as normally to direct all drainage toward one of said connections.

5. A method for conditioning paper machine 50

felts while moving at high speed, the performance of said method being confined to a limited area of the felt at any one time and being progressively extended across the width of the felt at such a rate as to assure treatment of the entire length of each widthwise element of the felt, said method comprising subjecting the felt passing over said limited area to a series of rapidly repeated conditioning cycles, each cycle including the injection of cleaning fluid into the felt immediately followed by vacuum extraction of a portion, at least, of the fluid injected, said vacuum extraction in each cycle being simultaneously accompanied by a scraping of the felt surface whereby progressively to increase the porosity of the felt from cycle to cycle.

6. A felt conditioner shoe including a plate adapted to contact one side only of a moving felt and of less width than said felt; there being in said plate, located to make contact with said felt, a plurality of means for supplying cleaning fluid to said felt and a plurality of means for applying vacuum to said felt, a portion of each of said vacuum applying means being effective to scrape the surface of the felt; said fluid supplying means and said vacuum applying means being alternated in a direction parallel to the travel of said felt, there being a sufficient number of each of said means to provide a plurality of cycles of fluid supplying and vacuum extraction of the fluid applied.

7. A felt conditioner shoe including a plate adapted to contact one side only of a moving felt and of less width than said felt; there being in said plate, located to make contact with said felt, a plurality of means for supplying cleaning fluid to said felt and a plurality of means for applying vacuum to said felt, a portion of each of said vacuum applying means being effective to scrape the surface of the felt; said fluid supplying means and said vacuum applying means being alternated in a direction parallel to the travel of said felt, there being a sufficient number of each of said means to provide a plurality of cycles of fluid supplying and vacuum extraction of the fluid supplied, certain of said vacuum applying means being effective over elongated areas inclined to the path of travel of said felt whereby to increase the scraping effect aforesaid.

THOMAS S. JORDAN.
